United States Patent Office

Des. 180,835
Patented Aug. 20, 1957

180,835

CANDELABRA

Harry H. Le Vine, Brooklyn, N. Y.

Application December 24, 1956, Serial No. 44,309

Term of patent 3½ years

(Cl. D48—2)

Fig. 1 is an elevational view of the candelabra of the present invention;

Fig. 2 is a top plan view of the same; and

Fig. 3 is one end view of the same.

I claim:

The ornamental design for a candelabra as shown.
